Primary Examiner — Elizabeth J Oswecki(74) *Attorney, Agent, or Firm* — Porter, Wright, Morris & Arthur, LLP(57) **CLAIM**

The ornamental design for a footwear heel, as shown and described.

DESCRIPTION

FIG. 1 is a perspective view of a first embodiment of a footwear heel showing our new design;

FIG. 2 is a left side view thereof, the right side view being a mirror image thereof;

FIG. 3 is a front view thereof;

FIG. 4 is a rear view thereof;

FIG. 5 is a top plan view thereof;

FIG. 6 is a bottom plan view thereof;

FIG. 7 is a perspective view of a second embodiment of a footwear heel showing our new design;

FIG. 8 is a left side view thereof, the right side view being a mirror image thereof;

FIG. 9 is a front view thereof;

FIG. 10 is a rear view thereof;

FIG. 11 is a top plan view thereof; and,

FIG. 12 is a bottom plan view thereof.

In the drawings, the broken lines in FIGS. 1-12 depict portions of the design that form no part of the claim.
